JOHN A. DEASY, OF LOS ANGELES, CALIFORNIA, ASSIGNOR OF ONE-HALF TO BRUNO H. SCHINDLER, OF SOUTHGATE, CALIFORNIA

BOLT

Application filed April 11, 1927. Serial No. 182,659.

This invention relates to sliding bolts of the type adapted for use on doors and the like, and it is the object of the invention to provide an extremely simple and inexpensive construction tensioning the bolt in its guide bracket and limiting its retraction and projection while providing convenient means for assembling the device.

More particularly it is the object of the invention to provide for inexpensive manufacture by stamping out the guide bracket at one operation so that integral parts of the bracket form means for tensioning the bolt and limiting its movement, the bolt being adapted for mounting in the bracket by merely a sliding engagement and without the necessity for skilled manipulation of any kind.

Further objects of the invention will be readily understood from the following description of the accompanying drawings, in which:

Fig. 1 is a perspective view of the device.

Fig. 2 is a vertical longitudinal section 25 through the same.

Fig. 3 is a transverse section on the line 3—3 of Fig. 2.

The guide bracket for the bolt is adapted for mounting on a door or the like in usual manner, and is stamped out at one operation so as to form not only the guide loops for the bolt and the openings for mounting screws, but also provide an abutment for limiting movement of the bolt and a protuberance for 35 tensioning the bolt in its guide loops.

As in instance of such construction an elongated plate 1 may be formed with lateral ears 2 having openings 3 adapted to receive suitable mounting screws, and guide loops 4 curve 40 outwardly from the plate and are formed by making pairs of parallel transverse slits in the plate in longitudinally spaced relation. The rear end of the plate, shown at 1^a, projects longitudinally beyond the rear ears 2 and loop 4 and at its outer end has an abutment 5 for limiting retraction of the bolt. The face of plate 1 is also provided with a protuberance 6 midway between the guide loops 4 and in longitudinal alinement there- 50 with.

The bracket as thus described is an integral structure formed by a single stamping operation, the abutment 5 and protuberance 6 being made by indenting the underside of plate 1 and thereby raising the face thereof, 55 at the same time that the outline of the plate is stamped out and the openings 3 and the slits for loops 4 are formed therein and the guide loops are curved outwardly from the plane of the plate.

A bolt 7 is adapted to slide longitudinally of plate 1 in guide loops 4, and at its underside is preferably flat and forms one continuous plane surface as shown at 8. An operating knob 9 projects from the bolt adjacent 60 its rear end so that it is in back of the rear guide loop when the structure is assembled as shown in Fig. 1, the parts being so arranged that when the bolt is projected to 65 operative position with its forward end extending beyond its supporting bracket its movement is limited by abutment of knob 9 against the rear guide loop 4, and when the bolt is retracted to inoperative position with 70 its forward end no longer projecting beyond the supporting bracket the rear end of the bolt is engaged by abutment 5 in order to 75 prevent disengagement of the bolt from its support.

When mounting the bolt in its guide loops 80 the rear end 1^a of the supporting plate is bent downwardly as shown in dotted lines in Fig. 2 so that the bolt will clear abutment 5 when being slipped into the loops; and with the parts thus assembled the flat underside of the bolt is slidably engaged by protuberance 6 so that the latter tensions the bolt against its guide loops and thereby prevents rattling.

After assembling the parts the plate end 90 1^a is bent back into normal position in the plane of plate 1 so that abutment 5 is adapted for engagement by the rear end of the bolt; and when the supporting bracket is mounted on a door or the like the screws extending 95 through openings 3 tighten the entire plate structure against the surface of the door so that the end 1^a is retained in normal position preventing displacement of the bolt.

The construction thus prevents rattling or 100

accidental sliding movement of the bolt and limits its retraction and projection so as to maintain assembled relation; and the device may be inexpensively manufactured since the entire supporting bracket is formed at one operation and the bolt is mounted therein by simply a sliding engagement requiring no tedious or skilled assembling operation.

I claim:

- 10 A latch construction comprising a plate having longitudinally spaced pairs of parallel transverse slots with the plate between the slots of each pair struck upwardly to form longitudinally spaced guide loops, a
- 15 protuberance struck up from the plate in rear of the guide loops, the rear end of the plate which carries said protuberance being adapted to be bent downwardly, a bolt inserted in the guide loops when the rear end
- 20 of the plate is so bent, the rear end of the plate being adapted to be bent back into the plane of the plate after the bolt is inserted in the guide loops so that the said protuberance is adapted for abutment by the
- 25 rear end of the bolt for limiting its retraction in the guide loops, and a protuberance struck up from the plate without breaking in the direction of sliding movement of the bolt, said last mentioned protuberance under-
- 30 lying and engaging the bolt between the guide loops for tensioning the bolt against said guide loops.

In testimony whereof he has affixed his signature to this specification.
